United States Patent Office.

JOHN B. RITTENHOUSE AND JOSEPH COLLINS, OF LOCUST LANE, PENNSYLVANIA.

Letters Patent No. 104,355, dated June 14, 1870.

IMPROVEMENT IN RAILWAY GATES.

The Schedule referred to in these Letters Patent and making part of the same.

To all whom it may concern:

Be it known that we, JOHN B. RITTENHOUSE and JOSEPH COLLINS, of Locust Lane, in the county of Indiana and State of Pennsylvania, have invented a new and improved Railway-Gate; and we hereby declare that the following is a full, clear, and exact description of the construction and operation of the same, reference being had to the accompanying drawing making part of this specification, in which—

Figure 1 is a transverse sectional elevation, and Figure 2 is a plan view.

This invention has for its object to enable a locomotive-engine to automatically open the gates placed across a railway-track, for the purpose of preventing cattle from straying thereon to places whither they should not wander.

The invention consists in connecting the pivoted gate-posts by means of stiff rods, with bars laid along the track, in such position that the locomotive may strike them, thrust them to each side, and thereby cause them to turn the gates open by means of the connecting-rods, the bars being furnished with springs which throw them into their original position as soon as the train has passed.

In the drawing—

A A are the track-rails.

a a are bars, of wood or iron, or both combined, whose ends are pivoted to one of the ties at b b, outside the track, while their opposite extremities lie on the rails A, flush with the inner sides of the same, at points between the side gate frames B B.

c c are bars similar in all respects to the bars a a, to which they are jointed at the ends between the gate frames, while the opposite extremities of the bars c are pivoted to one of the ties at the points d d, on the other side of the gate from the points b b, where the bars a are pivoted.

C C are the gates extending directly across the track and meeting at the center.

The gates are set in vertical posts e, which form the central standards of the side frames B, the posts e having cylindrical tenons at top and bottom, which enter mortises made to receive them in the tie h, and also in the lateral beams B B, placed at the tops of

the side standards, so that the posts e may swing easily.

Rods i i, parallel with the gates, connect one of the bars c with the gate-posts, by means of staples protruding from the sides of the latter; hence, when the locomotive strikes the bars a or c, according to the direction in which it moves, it throws the bars to each side, and, by means of the connecting-rods i, throws open the gates in opposite directions.

As long as any part of the train is between the bars the gates are in this manner held open, but, as soon as the train is clear of the bars, the springs k k, one of which is coiled about the side vertical standard l, and bears against one of the bars c, and the other of which is coiled around the side vertical standard m, and bears against one of the bars a, press the bars a c inward to their former position, where they lie in readiness for the next train.

The rods i serve also as stops, to limit such inward movement of the bars a c, under the impulse of the springs.

The bars c and a are rabbeted, so that those parts of them which extend beneath the cow-catcher may be of the requisite thinness, two inches, and the remaining portion outside the cow-catcher may be at least four inches thick.

The cow-catcher is provided with friction-rollers, which strike the raised parts of the bars and throw them open.

The thin parts of the bars extend inward to the wheels, and by them the bars are held open.

Having thus described our invention,

What we claim as new, and desire to secure by Letters Patent, is—

The bars a c, jointed together at their ends, and pivoted at their opposite extremities to ties, in combination with the connecting-rods i, swinging gates C, and springs k, substantially in the manner described, and for the purpose set forth.

JOHN B. RITTENHOUSE.

JOSEPH COLLINS.
